UNITED STATES PATENT OFFICE.

CONWAY MONCURE BLUME, OF ORANGE, TEXAS.

TREE SURGERY.

Application filed May 22, 1924. Serial No. 715,160.

To all whom it may concern:

Be it known that I, CONWAY MONCURE BLUME, a citizen of the United States, residing at Orange, in the county of Orange 5 and State of Texas, have invented certain new and useful Improvements in Tree Surgery; and I do hereby declare the following to be a full, clear, and exact description of the invention, such as will enable others 10 skilled in the art to which it appertains to make and use the same.

The present invention relates to tree surgery, and more particularly to an improved process of treating diseased and partly decayed trees and in an improved construction of filler to prevent further decay and seal the cavity made by the removal of the decayed wood.

An object of this invention is to provide a 20 one piece filler which is flexible to the required extent, so that the filler may bend with the trunk of the tree as the latter is swayed by wind and the like and without breaking and cracking the one piece filler 25 throughout its entire length.

Another object of the invention is to provide a filler for use in tree surgery which is so constructed in one piece that it will offset 30 all disadvantages heretofore found with fillers made in sections as these sections gradually work against each other and effect the displacement of the sections and consequently the opening of the cavity so that moisture, rain and seepage are permitted to enter the 35 cavity formed in the tree.

A further object of the invention is to provide a one piece filler with compressible and expandable inserts, so arranged as to permit of the free flexing of the filler and at 40 the same time distribute the flexing or bending throughout the entire length of the filler and thus offset the cracking or breakage of the filler. It is the cracking or breakage of the filler which is to be overcome and this is 45 accomplished by the peculiar arrangement of the reinforcements and of the compressible portions.

A still further object of the invention is to provide reinforcing bolts or braces and to 50 so position the same and to form peculiar shaped countersinks for the heads and nuts of the bolts as to cause the bark of the tree

to roll over the enlarged ends of the braces and entirely cover and enclose the same after a relatively short period of time. 55

A further object of the invention is to provide means for protecting the wood against the action of the metal and against moisture and also to provide means for cushioning the filler against the wall of the cavity to permit of a reasonable flexing or bending of the trunk or large limb of the tree which is treated.

With the foregoing and other objects in view, the invention will be more fully described hereinafter as to both the method of treating trees and the article used in carrying out the method and will be more particularly pointed out in the claims appended hereto. 70

In the drawings, which show the structure of the article produced, and wherein like symbols refer to like or corresponding parts throughout the several views:

Figure 1 is a side elevation of the trunk 75 of a tree which has been treated according to the present invention and to which is applied a filler constructed according to the present invention.

Figure 2 is a fragmentary vertical section 80 taken through the same substantially on the line 2—2 of Figure 1.

Figure 3 is a transverse section taken through the upper portion of the treated tree trunk, showing the arrangement of the 85 braces with their countersunk ends, and also showing the positions of the adjacent compressible inserts.

Figure 4 is a similar view taken on the line 4—4 of Figure 1. 90

Figure 5 is a side elevation of the lower end of a tree trunk according to the present invention and showing a slightly modified form of filler applied thereto.

Figure 6 is a fragmentary vertical section 95 taken through the same substantially on the line 6—6 of Figure 5.

Figure 7 is a transverse section through the lower end of the tree trunk and filler substantially on the line 7—7 of Figure 5, and 100

Figure 8 is a similar view taken on the line 8—8 of Figure 5 and showing the arrangement of the single transverse brace.

Referring to the drawings, and first to

Figures 1 to 4, both inclusive, 10 designates the trunk of a tree or the like which is to be treated according to the present method and with the filler of this invention.

5 The first step in the method or process is to remove all of the diseased and decayed wood and other foreign matter from the tree by making, for each location, a cavity 11 which is oblong in shape and lengthwise 10 or vertically of the trunk 10 and which has its upper and lower extremities tapered into relatively sharp points 12.

15 The cavity 11 is provided at its front, or where it opens through the side of the trunk 10, with undercut or forwardly converging walls 13 which are preferably flat and which diverge inwardly to an angle which is sufficient to hold the filler in place. According to the nature of the diseased portion 20 of the tree 10, the cavity 11 is more or less irregular and the wood of the tree will have to be removed or cut away to eliminate all of the diseased or decayed wood or other foreign matter so as to leave nothing but 25 the healthy wood which will not promote decomposition.

30 From Figure 2 it will be noted that the top wall 14 of the cavity is inclined outwardly and downwardly and that the bottom wall 15 is disposed substantially parallel thereto or is inclined downwardly and outwardly so as to drain off any water, seepage or the like which might tend to pocket in the cavity and promote decomposition.

35 After the cavity has been thoroughly cleansed of all foreign matter, the wall of the cavity is painted or coated with a creosote mineral and vegetable oil to provide a preservative coating 16 for the wood to prevent further decay. After this coating 16 is thoroughly dry, a layer 17 of plastic asphalt is then applied to seal any opening that might later occur, and to also serve as 40 an elastic packing between the wall of the cavity 11 and the filling of cement which is to be applied. After this plastic coating of asphalt 17 is applied the cavity is left open to the atmosphere for a period of from four to eight days in order to allow the asphalt 45 to become thoroughly hardened.

50 After the drying period has elapsed, the trunk is then braced at the cavity 11 and these braces comprise elongated bolts 18 having heads 19 on one end and nuts 20 on 55 the other end. These braces 18 may of course be positioned in any suitable manner in the tree trunk 10, but preferably they are disposed as shown with a single brace 18 disposed transversely through the 60 lower portion of the cavity 11 and substantially parallel with the face thereof. Spaced a suitable distance above the single transverse bolt 18 is a pair of bolts or braces 18 which are crossed and extend substantially 65 diagonally through the cavity 11, and have

their opposite ends terminating in the rear sides of the tree trunk 10. These braces 18 may be disposed in any suitable number and are preferably arranged in singles and pairs which alternate throughout the height of 70 the cavity 11.

75 These bolts 18 are preferably heavily coated with asphalt to offset corrosion and decay and also to prevent any deleterious action on the surrounding wood incident to the corrosion. The heads or enlarged ends 19 and 20 of the braces 18 are countersunk not only through the bark, but also to the level of the wood or cambium line, so that no resistance will be offered to the new wood 80 as it rolls over the heads 19 and 20.

85 Another important feature of the method or process is in making these countersinks of substantially the same general contour as the cavity 11 or making them in the form of elongated depressions as shown at 21 with tops and bottoms which are sharply converged or pointed so that the new wood may roll over upon the heads of the braces 90 and into an oblong seam.

95 After the braces 18 have been positioned the cavity 11 may now be filled and such filling is made into an homogeneous mass comprising preferably a mixture of two parts of screened sand and one part cement. Of course these proportions and ingredients may be varied as circumstances demand without departing from the spirit of this invention. This mixture is dampened very slightly to form a plastic mass which may be 100 tamped into the cavity and which will hold its shape without the aid of a supporting wall or mold board. The filling process is preferably started from the bottom point of the cavity 11 and the mixture is tamped 105 into the cavity slowly and evenly until the desired height is reached. As soon as the desired height is reached the top surface is smoothed off, so as to incline forwardly or outwardly and also incline downwardly from lateral side of the cavity 11. A filler plate 110 22 is laid upon the top surface so formed and the process of packing or tamping the cement mixture is continued. It will be noted that the filler plates extend from one side of the cavity to substantially two-thirds ($\frac{2}{3}$) the distance across the cavity so as to pass the center. The filler plates 115 22 are of sufficient thickness to permit of the compressing of the same to the desired extent when the trunk of the tree is swayed laterally in either direction and at the same time to support the superposed mass of cement without cracking or breaking the same.

120 In a cavity of the usual or average size the bottom portion of the filler is substantially eight inches high below the first filler plate 22. The material is tamped continuously and in an integral mass about the lower end 125 of the filler plate 22 and above it until a 130

height of about four inches is reached when top of the mass is again smoothed off into a forwardly and inwardly inclined surface which extends from the opposite wall 5 of the cavity 11 approximately two-thirds ($\frac{2}{3}$) of the distance across the cavity, so as to overlap the prior formed inclined surface. A second filler plate 22 is now placed upon the opposite inclined surface, and the process 10 is continued throughout the height of the cavity 11. The filler plates 22 are thus arranged in staggered or offset relation and slightly overlapped, the same being inclined inwardly toward and past the central line 15 of the cavity 11 and outwardly toward the open side of the trunk 10. Such arrangement provides for the shedding of water and the draining off of seepage and other accumulations which tend to destroy or 20 otherwise impair the wood or the filling.

It will be noted from Figures 2, 3 and 4 particularly, that the braces 18 are embedded into the cementitious mass, so that the mass is thoroughly supported and interposed at 25 different points throughout its height to prevent the cracking or breaking apart of the mass into separate sections because it has been found that when separate sections are used they work against each other and cause 30 displacement of the sections with the consequent formation of pockets and crevices into which seepage and the like may accumulate and cause decomposition and destruction of the tree and the filler.

35 The filler, designated generally by the numeral 23, is thus a one piece integral mass filling cavity 11 and which is provided with the inwardly extending and downwardly and forwardly inclined slits at its 40 opposite edges to receive the filler plates 22. As these slits are arranged in offset or staggered relation there is left a continuous and uninterrupted column of cementitious material extending from end to end of the cavity 45 11 and which is permitted to flex within the limits of the material and throughout its entire length, and is supported by the filler plates 22. Therefore, as the trunk 11 is flexed back and forth there is no danger 50 of separate parts of the filler working against each other and causing relative displacement. The mass, as a whole, is held in between the walls 13 and cannot break up or separate and 55 no part of the same can be dislocated.

55 In Figures 5 to 8 inclusive a slight elevation is shown wherein the cavity 24 is formed in the base of the trunk 25 of the tree and is substantially inverted V-shape. In this case the cross-section structure of 60 the cavity is substantially the same as above described with the beveled or forwardly converging walls 26 at the forward part of the cavity for holding the filler 27 in place. It will be noted that all the other details of 65 construction and the method of forming and

filling the cavity are otherwise identical as above described.

In both forms of the invention it will be noted that the filler is in one piece and comprises a single mass having the inwardly 70 and forwardly extending slits at its opposite edges to receive the filler plates 22. These filler plates 22 may be of any suitable composition but preferably are of an asbestos based composition paper or roofing 75 shingle which is capable of being compressed and which will tend to expand into normal position for maintaining the slits closed at all times.

It is obvious that various changes and 80 modifications may be made in the details of construction and design of the above specifically described embodiment of this invention without departing from the spirit thereof, such changes and modifications being 85 restricted only by the scope of the following claims:—

What is claimed is:—

1. A filling for tree cavities comprising a homogeneous mass adapted to fill the cavity and provided with flexible inserts 90 extending inwardly at an obtuse angle and in staggered relation from the opposite edges of the filler to permit flexing of the filler throughout its length and to prevent cracking thereof.

2. A filler for treating cavities comprising a body portion composed of an integral elongated mass adapted to fill the cavity 100 and provided with diagonal slits extending inwardly from the opposite edges of the mass and in staggered relation relatively to each other, and packing plates fitted in said slits adapted to support the mass against cracking and permit of the flexure of the 105 mass from end to end.

3. A filler for treating cavities comprising a monolithic body mass adapted to fill the cavity and having longitudinally spaced 110 apart slits in its opposite edges with the opposed slits arranged in staggered relation to provide an integral serpentine connecting portion throughout the entire length of the mass and compressible inserts fitted in said slits adapted to support the side portions of the mass and prevent cracking of the serpentine connecting part thereof and adapted to distribute the flexing of the mass throughout its entire length.

4. That method of treating diseased 120 trees which comprises forming a cavity therein by removing the diseased and decayed wood and other foreign matter from the tree and forming an elongated cavity 125 therein, placing a coating of creosote mineral and vegetable oil on the inner wall of the cavity and permitting to dry, placing a heavy layer of plastic asphalt over said creosote coating to seal the walls of the cavity 130 and to provide a cushioning layer in the

cavity, permitting said plastic asphalt coating to thoroughly dry and become hard, placing braces through the trunk of the tree to intersect the cavity and coating the 5 braces with plastic asphalt to prevent decomposition of the wood thereabout, and tamping a cement mixture in the cavity against the cushioning layer and about said braces and embedding in the plastic mass at 10 suitable intervals and into opposite edge portions of the mass compressible filler plates and inclining the same inwardly and forwardly in spaced relation throughout the height of the mass.

15 5. That method of practicing tree surgery which comprises cutting out an elongated and oppositely pointed cavity in a tree to remove all decayed and diseased

wood and the like therefrom and making 20 forwardly converging walls at the front of the cavity, placing a cushioned layer of asphalt against the inner wall of the cavity, positioning reinforcing braces through the tree and in position to intersect the cavity, tamping a cementitious mass in the cavity 25 against said cushioning layer and about said braces to form an integral filling member for the cavity, and embedding in the cementitious mass during formation thereof compressible filler plates in the opposite edges 30 of the mass and in inwardly and forwardly inclined positions and in substantial spaced apart relation one above the other to support the mass and permit flexing of the same throughout its length.

CONWAY MONCURE BLUME.
